UNITED STATES PATENT OFFICE.

JOHN E. KILKER AND CHARLES W. DAKE, OF CHICAGO, ILLINOIS, ASSIGNORS TO PYLE NATIONAL ELECTRIC HEADLIGHT COMPANY, OF CHICAGO, ILLINOIS, A CORPORATION OF NEW JERSEY.

DESIGN FOR A HEADLIGHT-CASING.

50,623.

Specification for Design.

Patented Apr. 17, 1917.

Application filed March 18, 1916. Serial No. 85,224. Term of patent 14 years.

To all whom it may concern:

Be it known that we, JOHN E. KILKER and CHARLES W. DAKE, citizens of the United States, residing at Chicago, in the county of Cook and State of Illinois, have invented a new, original, and ornamental Design for a Headlight-Casing, of which the following is a specification, reference being had to the accompanying drawing, forming part thereof.

The figure is a perspective view of a headlight casing showing our new design.

We claim:

The ornamental design for a headlight casing as shown.

JOHN E. KILKER.
CHARLES W. DAKE.
